RADIATOR BOX BASE

Filed Aug. 28, 1926

2 Inventor,
Clarence C. Shepp,
By Minturn & Minturn
Attorneys.

UNITED STATES PATENT OFFICE.

CLARENCE C. SHIPP, OF INDIANAPOLIS, INDIANA.

RADIATOR BOX BASE.

Application filed August 28, 1928. Serial No. 132,169.

This invention relates to improvements in housing boxes for steam radiators, and more particularly to the box base and manner for connecting said box base with the superimposed sides of the box.

Heretofore the sides and base have been lapped and riveted together, with the result that unequal expansion has caused the box members to buckle and spread apart between the rivets, thereby reducing the draft through the housing box, and admitting vitiated air to the box from the room in which the radiator is located, instead of drawing in fresh air from outside of the building, as is desired.

One object of this invention is to provide a simple slip-joint between the box base and walls, that will not buckle nor open up but which will be practically air tight under all temperatures and all conditions of use.

Another object is to make the base as well as the box, in two separable parts, adapted to be assembled at the rear and front, respectively, of a radiator, the box and base members for the rear being capable of complete assembly, for convenience, before those for the front are assembled.

A further object is to improve on the details of construction in a manner which will hereinafter appear and which will be specified in the claims.

I accomplish the above objects by the construction illustrated in the accompanying drawing, in which—

Fig. 1, is a perspective view of a steam radiator with my invention in operative assembly therewith;

Fig. 2, is a fragment in perspective of a box base embodying my invention and here shown detached from the radiator coils, but with a box front in vertical section, in position in the box base. In this embodiment the box base differs from that shown in Fig. 1, in that while the front and rear are level in the latter, the front in Fig. 2, is lower than the rear, both forms being used;

Fig. 3, is a top plan view of the box base shown in Fig. 2, but without the box front being shown;

Fig. 4, is a vertical section on the line 4—4 of Fig. 1, except that the front of the box base is lowered as in Fig. 2;

Fig. 5, is an enlarged cross section of the

joint between the box and base shown in Fig. 4;

Fig. 6, is a section on the line 6—6 of Fig. 1 showing a detail of the slip joint between the front and back members of the box;

Fig. 7, is a front view of the plate which is inserted to close the space above the bosses at the steam connections between the radiator coils; and

Fig. 8, is a sectional detail similar to Fig. 5, showing a modified form of joint.

Like characters of reference indicate like parts in the several views of the drawing.

The coils 8 are of a construction usual to steam radiators. They have bottom openings for the passage of steam, surrounded by bosses 9, from which the box base 10 is suspended by bolt hooks 11, which pass through eyes 12, projecting from the ends of the box. 13 is the radiator containing box.

As the box and base are both assembled after the radiator is installed, they are both made in two longitudinally separable parts.

The box base 10, has a tubular extension 14 on its wall side corresponding in size and shape with the air duct through the wall of the house to the outside air. This tube is surrounded by a flange 15 which is fastened flat against the wall around the opening, and a sleeve extension 16' enters the wall opening. In the bottom of the box, and extending into the tube close to flange 15, and for substantially the whole length of the box, is a hole 16 which is opened and closed by a door 17, hinged at its edge next to the flange.

The ends 18, 18, of the box have openings 19 for the passage therethrough of the bosses 9, and in practice the metal above the opening is removed as shown for greater convenience in assembly with the radiator, but this is not essential. The separation of the base into two parts, front and rear, is accomplished by dividing the ends 18, 18, on the lines 20, which extend diagonally beginning with the outer corners of the hole 16.

An angle bar 21 is riveted to the inside bottom of the back base member with an end overlapping the bottom of the front member, to which and to the adjacent side of the base, the end is removably secured by screws. This angle bar construction is duplicated for

both ends of the base, and by this means the two parts of the base are readily separated and united.

Figs. 2 and 4 show the back member of the base higher than the front, but this depends upon the size of the outside air inlet, which varies. Fig. 1, shows a different base, in this respect, for a narrow opening.

The top longitudinal edge 22 of the base 10 in front is set in or indented by an ogee curve 23, to form a recess for a channel bar 24, here shown as formed out of a strip of corrugated sheet metal having one edge bent and hooked over edge 22, and the opposite 15 portion bent to form a channel 25. Preferably the edge opposite the hook is bent in, as shown in Fig. 5, to reinforce and finish that edge, and also, to lower that side of the channel sufficiently below the opposite side 20 to cause the latter to act as a guide in slipping the edge of the front box member into place in the channel. Without such projection the edge under insertion would buckle or push past the channel, but with it, the 25 projection arrests and guides the metal sheet into the channel.

Ears 26, at the ends of the channel bar, are formed out of the latter and are bent over against the ends of the base and are 30 spot-welded or riveted there.

A similarly formed channel bar is hooked over the top edge of the rear member of the base.

In Fig. 8, is shown a channel bar of a 35 modified form in which the bar, instead of having a hooked edge to hook over the base is secured to the latter by rivets.

The box proper is preferably formed out of corrugated sheet metal, in two major 40 members 27 and 28, divided midway at the ends, vertically, and united by slip joints 29, (see Fig. 6). The top longitudinal edges are stiffened and finished by rolls 30, and the ends by channel bars 31.

45 The open spaces existing at the ends of the base above the bosses 9 are closed by plates 32. Each plate makes a snug fit against the front and back walls of the box and has a bottom, half-round recess 34 to receive the 50 boss on which it rests when in use.

This invention may be varied without departing from the spirit of the invention, and I therefore do not desire to be limited more than is required by the appended claims.

55 I claim:

1. A radiator box base having end members with half-round openings at their bottoms and having a bottom door opening in the rear half of the base, said base being 60 in two parts divided longitudinally of the bottom at the front line of the door opening and obliquely from the door opening toward the middle of the half round openings and means for removably securing the 65 parts in assembled position.

2. A radiator box having a bottom door-opening, said base being in two parts divided at the front line of the door opening and means for removably securing the parts in assembled position, comprising a plurality 70 of bars crossing the meeting line of the members and secured to both members, and removably secured to at least one of them.

3. A radiator box base having a bottom door-opening, said base being in two parts 75 divided at the front line of the door opening and means for removably securing the parts in assembled position, comprising an angle bar riveted to the inside of one member and secured by screws to the other. 80

4. A radiator box base having a longitudinal edge indented for the attachment thereto of a channel bar, a channel bar formed out of a separate piece attached to the base, and a box of corrugated metal removably seated in the channel of the bar. 85

5. A radiator box base having a longitudinal indented edge, a channel bar formed out of a separate piece of corrugated metal and secured to the base in said indentation, 90 and a box of corrugated metal removably seated in the channel of the bar.

6. A radiator box base having a longitudinal indented edge, a channel bar formed out of a separate piece of metal in said indentation having a turned edge hooked over the edge of the base, and ears welded to the base, and a box removably seated in the 95 channel of the bar.

7. The combination, with a radiator, of a 100 radiator box base having a longitudinal edge, a channel bar having a turned edge hooked over the edge of the base and having end ears fastened to the ends of the base, and a box seated in the channel of the bar. 105

8. A radiator box base in two longitudinally divided parts, means for attaching the rear part to the wall of a room, hook means for attaching the front part to the radiator, and bar means for removably securing the two parts together. 110

9. The combination, with a radiator box base having front and rear longitudinal edges, of a channel bar of corrugated metal for each edge having a turned edge hooked 115 to a respective one of said base edges, and a radiator box of corrugated metal seated in the channel bars. 115

10. The combination, with a radiator box base having front and rear longitudinal edges, of a channel bar of corrugated metal for each edge having an edge fastened to a respective one of said base edges, and a radiator box of corrugated metal seated in the channel bars, one of the sides of each channel being higher than the other to guide the radiator box into the channel. 120 125

11. The combination, with a radiator having sections and connecting steam pipes, of a radiator box base having ends cut away 130

for the passage of the steam pipes, a radiator box secured to the base having ends cut away for the passage of the steam pipes and plates to close the openings caused by said 5 cut away portions of the box and base.

12. The combination, with a radiator box-base having front and rear longitudinal edges, of a channel bar of corrugated metal for each edge having a turned edge hooked 10 to a respective base edge, a radiator box of corrugated metal seated in the channel bars, said box having ends each in two vertically

divided members, and slip joints meeting the divided edges of the box ends. 15

13. A radiator box base comprising a bottom in two longitudinally divided parts the rear of which has a door-opening, and two end members each having a radiator-boss opening half round at the bottom, and a joint extending downwardly from substantially the lowest portion of the half round opening obliquely to the door opening. 20

In testimony whereof I affix my signature.
CLARENCE C. SHIPP.
